(57) **CLAIM**

The ornamental design for a gaming machine cabinet as shown and described.

DESCRIPTION

FIG. 1 is a first front perspective view of a gaming machine cabinet of our new design.

FIG. 2 is a second front perspective view of the gaming machine cabinet of FIG. 1.

FIG. 3 is a third front perspective view of the gaming machine cabinet of FIG. 1.

FIG. 4 is a front view of the gaming machine cabinet of FIG. 1.

FIG. 5 is a rear view of the gaming machine cabinet of FIG. 1.

FIG. 6 is a left side view of the gaming machine cabinet of FIG. 1.

FIG. 7 is a right side view of the gaming machine cabinet of FIG. 1.

FIG. 8 is a top view of the gaming machine cabinet of FIG. 1; and,

FIG. 9 is a bottom view of the gaming machine cabinet of FIG. 1.

The dashed broken lines in the drawings illustrate portions of the gaming machine cabinet that form no part of the claimed design.

1 Claim, 9 Drawing Sheets
